ARTIFICIAL FOOT

Stanley R. Fogg, Terre Haute, Ind.

Application April 23, 1946, Serial No. 664,298

9 Claims. (Cl. 3—6)

1

This invention relates to an artificial foot and ankle construction by which is made available to the wearer, when pressure is exerted upon the foot portion thereof, all of the various actions, and particularly rectilinear actions, which is possible in a natural foot.

An object of the invention is to provide a novel relatively simple and light weight artificial foot, for permitting the natural action thereof, as in a natural foot, and which is provided with an ankle plate connected and supported relative to the sole portion, in such a manner as to give a spring cushioning and retarding effect similar to the movement of the foot at the ankle joint in a natural foot, and to compensate for the rectilinear action of the foot and angularly with respect to the leg at the ankle joint, which will raise the sole and toe of the foot or lower the same, in the progressive steps as in walking, and also to provide a novel joint and spring connection at the toe which will clear the toe of the ground, the same as in a human foot, as a step is completed and the weight of the body is removed from the back of the foot.

A further object of the invention is to provide a novel pivot joint at the ankle and hydraulic spring cushioning means therefor in conjunction with an ankle plate to which the leg proper is connected, and also a novel ball and socket joint associated with a spring for connecting the pivoted toe section of the foot to the sole thereof at the back thereof, where it joins with the ball of the sole.

Other objects and advantages reside in the details of construction and operation as more fully hereinafter described and claimed, reference being had to the accompanying drawings forming part hereof, wherein like numerals refer to like parts throughout, and in which:

Figure 1 is a perspective view of an artificial foot constructed in accordance with the invention.

Figure 2 is a side elevation partly in section at the ankle joint and cushioning means at the heel of the foot.

Figure 3 is a view similar to Figure 2 but with the leg portion abbreviated and showing the action of the parts when taking a step.

Figure 4 is an enlarged detail sectional elevation of the ankle joint pivot.

Figure 5 is a detail sectional plan view of the hydraulic cushioning control means, and

Figure 6 is a detail sectional elevation of the resilient connection between the sole and toe.

Referring to the drawings in detail, in which

2

like reference characters designate corresponding parts throughout the several views, the improved artificial foot is shown as comprising a sole plate 10 having a heel portion 11, an arch portion 12 and a toe portion 13. The toe portion 13 is hinged or pivoted transversely across the sole at its juncture with the ball portion of the latter by means of pivots 14 engaging apertured ears 15 extending upwardly from opposite edges of the ball portion of the sole at the transverse pivot connection by means of a flange 16 extending transversely the full width of the toe portion at its rear edge and formed at the outer ends thereof, with the pivot pins 14, or vice versa. The toe portion is provided with a raised tapered convex frame designed to fit the toe of a shoe, as indicated at 17, and comprising a plurality of spaced longitudinal frame members or wires 18 of any suitable number, extending from the tip or rounded toe edge at the front and curved upwardly and rearwardly to join at their rear ends, as indicated at 19, to a transverse arched member 20 having its extremities curved downwardly and suitably anchored to the toe portion 13 as indicated at 21 as by riveting, welding, brazing, soldering or otherwise. The members 18 are spaced around the convex front edge of the toe portion 13 and correspondingly anchored at their front lower ends thereto in the same manner as the ends of the arch portion 20, as indicated at 22 and progressively shorter from the center to the outside members. At the rear ends of the outside members 18, which are similarly connected to the arched member 20, a transverse rectilinear frame member 23 is provided with its ends anchored thereto at such points as indicated at 24 and forming the chord of an arc of the arch portion 20 beneath the latter, between said points.

An expandable coil spring or other resilient means 25 is interposed in an inclined position rearwardly from the center of the arched portion 20 and connecting member 23 to the sole 10 in spaced relation rearwardly at the back of the toe frame 17, and may have its rear extremity 26 suitably anchored in an apertured ear or lug 27 secured centrally of the width of the sole on the ball portion thereof. The upper forward end of the expandable means or spring 25 is provided with a ball and socket connection with the toe frame permitting universal movement, and for this purpose, a hemi-spherical cup 28 is fitted or set in the forward end of the spring 25 at the end coils thereof, and has a flanged top edge 55 or rim 29 turned over the outside of the top coil

or convolution of the spring to grip and retain the cup in position. The flanged edge of the cup extends beyond the point of the largest diameter thereof, to receive and retain a ball member 30 therein for angular movement, and has a two point connection with the toe frame 17 by a multiple or pair of arms 31 rigid with the ball member and attached to the arched portion 20 and brace member 23 centrally of the lengths thereof and width of the toe at this point. The purpose of this arrangement is to give a round firm bearing surface for the collar supporting spring in order that the spring will remain in line at all times. At the same time, the toe portion 13 will be retained in rectilinear alignment with the sole portion and will be allowed the necessary angular movement with respect thereto, in walking, and permitting the rear portion of the artificial foot to move upwardly and downwardly relative thereto, as well as to cause the hinged toe portion to align with the sole properly by reason of the joint and resilient means or spring which controls the same, so that the natural recoil of the toe as the foot is lifted from the ground or at the completion of a step, is attained.

A suitable leg portion 32 is shown connected or pivoted for angular movement with respect to the foot portion at the ankle joint 33, and may comprise a suitable outer shell or wall as shown, with interior reinforcing and frame members or wires 34 bracing the same, in connection with an ovate or lenticular longitudinally extending ankle plate 35 at the bottom of the leg portion. For this purpose, the lower end of the leg portion at the shell and interior reinforcing frame 34, is rigidly attached to the top of the ankle plate, in any suitable way, as by riveting, welding, bracing, or otherwise.

Mounted between the ankle plate 35 and the heel of the sole is a hydraulically controlled ankle joint or pivot 36 including a cylindrical wrist pin 37 mounted in a hinge or sleeve comprising a central section 38 welded or otherwise fixed to the ankle plate 35 transversely, at a point intermediate the length thereof as shown at 39 and a pair of end sections 40 abutting the ends of the central section 38 around the wrist pin or hinge 37 with an interposed fibre or sound silencing and cushioning bushing 41 between the sections and the pin if desired. The sections 40 are supported at an elevated position spaced above the heel portion of the sole and held rigidly against turning, by a suitable frame structure including spaced parallel vertical rods 42, forwardly inclined and divergent rods 43 extending to the side edges and front end of the sole plate in rear of the toe portion 13 and anchored thereto, with a transverse upwardly arched intermediate brace rod 44 and downwardly divergent and slightly rearwardly inclined brace rods 45 at the back of the heel, all rigid with or fixed to the end sections 40.

A base plate 46 is mounted on the heel portion 11 of the foot plate or sole 10 and mounts a pair of front and rear vertical cylinders 47 spaced apart longitudinally and located centrally of the width of the heel and base plate with their upper ends positioned beneath the ends of the ankle plate, 35. Pistons or plungers 48 operate vertically in the cylinders 47 and have connecting rods 49 pivotally connected at 50 by suitable bearing brackets or otherwise, to the bottom face of the ankle plate 35. The plungers are normally held raised by central compression

springs 51 disposed between the pistons and the closed lower ends of the cylinders to give a desired degree of resistance and cushioning effect as well as upward movement of the cylinders in walking, during the angular movement of the foot and leg portions relative to each other and under the weight of the person equipped with an artificial leg and foot. This resistance and cushioning effect is increased by springs 52 concentrically encircling the springs 51 below the upper portions of the latter and also resting on the closed lower ends of the cylinders, so that under the extreme weight of the body or pressure in walking, greater resistance is offered to the downward movement outwardly of the pistons or plungers 48. A suitable hydraulic fluid, such as oil, or air, within the cylinders and the flow thereof from one cylinder to the other at the bottom may be effected through the medium of a by-pass or duct 53 in the base plate 46 or other form of conduit connecting the lower ends of the cylinder chambers and controlled by a needle valve or the like 54 operating in a threaded bore formed as a continuation of the longitudinal portion of the passage 53 at one end of the base plate or other interiorly threaded extension thereof and adapted to be turned by a T-head or pin 55 or other form of knob or handle, so as to control the flow of the fluid through the passage 53 at its vertical connection with the chamber of one of the cylinders 47, preferably, the forward one at the tapered end of the valve.

By the construction described, the ankle joint or pivot is hydraulically controlled but preferably allowed a full 90° arc of swing, while the toe portion at its hinged connection and resiliently or spring controlled as described, is allowed a maximum swing in an arc of 60°. Thus, in walking, proper angular movements are allowed relatively between the leg portion 32 and the foot at the ankle joint, and also between the toe plate and the sole. The two compensating hydraulic cylinders or cushioning means between the leg and thus the ankle plate and the foot plate or sole, automatically adjusts the position of the ankle plate with respect to the foot plate at the ankle joint and to the position which is natural to the function it is performing during the walking movement, so that at each step, as pressure is exerted upon the pistons, either the front or rear pistons or plunger is depressed within its cylinder, causing compression on its respective springs, first of the weaker springs 51, and then of the surrounding springs 52 until the maximum of the arc of swing is attained and the entire weight of a body applied to the artificial foot. While one piston is depressed, the other is raised on their outward and inward strokes, respectively, with the springs expanding or pressing against the pistons to maintain constant pressure between them and the foot plate or sole so that the ankle movement is accomplished in a smooth and noiseless manner. Also, by having the coil springs rest at all times in rubber cushioning discs 56 between the springs and the lower ends of the pistons to seal the hydraulic fluid within the cylinders and from escaping around the latter and between the same and the inner walls of the cylinders, is prevented by a simple and efficient form of packing. Thus, as the ankle plate tilts downwardly in front, the weight of the body transmitted by means of the framework to the toe, causes the spring 51 to be compressed or coil, elevating the plane of the rear of the sole at the ankle or hinged joint 33, as shown in Figure

3 of the drawings. As the weight is lifted, the spring 25 recoils, lifting the foot clear and permitting it to be swung forward to complete the step. On raising the foot from the ground, the spring 25 maintains the toe portion of the sole or foot plate 10 in alignment therewith as shown in Figures 1 and 2 of the drawings. Then, as the heel is set down, the action in the other cylinder by reason of the hydraulic cushion and spring action on the pistons, cushions the downward and rearward movement of the leg and foot at the heel, duplicating that of the forward piston in the first or initial stage of the step. This compresses the springs 51 and 52, until the foot is level on the ground, when the springs act uniformly tending to level the ankle plate 35 when the leg portion is vertical. This movement is cushioned by the resistance to the downward movement of the pistons by the fluid contained in the cylinder at the back, while pressing against the forward pistons, assisted by the action of the expansible springs therein. Adjustment of the needle valve controlling the passage of the fluid through the feeder tube or passageway produced by the duct 53, controls the volume of fluid passing into the respective cylinders on the opposite movement of the pistons therein, so that the walking action can be suited to the particular person and regulated to a nicety. This will also permit adjustment to compensate for the variations in the weight of different wearers.

Particular attention is called to the fact that the hinge flange which extends the full width of the toe plate or frame, swinging on the pin formed by the frame or ball portion of the sole plate 10, of the body of the foot, insures positive alignment of the plate portions at their pivoted edges, the purpose of the hinged flange being to make possible the same spring reaction which clears the toe of a human foot as a step is completed and the weight of the body is removed from the back foot. It should also be noted that all mechanical parts are located below the ankle plate and are therefore arranged compactly to facilitate the movements as well as the construction and assembly of the device and all parts may be of steel tubular construction, including the framework, if desired, assuring maximum strength and minimum weight.

In view of the foregoing description taken in conjunction with the accompanying drawings it is believed that a clear understanding of the construction, operation and advantages of the device will be quite apparent to those skilled in this art. A more detailed description is accordingly deemed unnecessary.

It is to be understood, however, that even though there is herein shown and described a preferred embodiment of the invention the same is susceptible to certain changes fully comprehended by the spirit of the invention as herein described and the scope of the appended claims.

What I claim is:

1. In an artificial limb, the combination with a lower limb portion, an ankle plate secured thereto, a sole plate pivoted at a raised point to the ankle plate, hydraulic cushioning means between the ankle plate and the heel of the sole plate in front and rear of the pivot, and means for controlling said hydraulic means, a connection through which the fluid passes from one to the other, and means for controlling the passage of fluid through said connection.

2. In an artificial limb, the combination with a lower limb portion, an ankle plate secured

thereto, a sole plate pivoted at a raised point to the ankle plate, hydraulic cushioning means between the ankle plate and the heel of the sole plate in front and rear of the pivot including cylinders mounted on the heel portion of the sole plate, plungers operating in said cylinders and having pivotal connection with the ankle plate, springs in said cylinders between the plungers and lower ends of the cylinders and cushioning the downward movement of the pistons in the cylinders, a passageway connecting the lower ends of the cylinders, a valve for controlling the flow of fluid through said passageway from one cylinder to the other, and a framework mounted on said sole plate.

3. In an artificial limb, the combination with a lower limb portion, an ankle plate secured thereto, a sole plate pivoted at a raised point to the ankle plate, hydraulic cushioning means between the ankle plate and the heel of the sole plate in front and rear of the pivot including cylinders mounted on the heel portion of the sole plate, plungers operating in said cylinders and having pivotal connection with the ankle plate, springs in said cylinders between the plungers and lower ends of the cylinders and cushioning the downward movement of the pistons in the cylinders, other springs in the cylinders and encircling the first springs to engage the plungers when forced downwardly, a passageway connecting the lower ends of the cylinders, a valve for controlling the flow of fluid through said passageway from one cylinder to the other, a toe plate pivoted transversely to the sole plate, and resilient means connecting the sole plate to the toe plate at a raised point thereon.

4. In an artificial limb, the combination with a lower limb portion, an ankle plate secured thereto, a sole plate pivoted at a raised point to the ankle plate, hydraulic cushioning means between the ankle plate and the heel of the sole plate in front and rear of the pivot including cylinders mounted on the heel portion of the sole plate, plungers operating in said cylinders and having pivotal connection with the ankle plate, springs in said cylinders and cushioning the downward movement of the pistons in the cylinders, a passageway connecting the lower ends of the cylinders, a valve for controlling the flow of fluid through said passageway from one cylinder to the other, a toe plate pivoted transversely to the sole plate, and resilient means connecting the sole plate to the toe plate at a raised point thereon, said resilient means having a universal joint connection between it and the raised point of the plate.

5. In an artificial limb, the combination with a lower limb portion, an ankle plate secured thereto, a sole plate pivoted at a raised point to the ankle plate, hydraulic cushioning means between the ankle plate and the heel of the sole plate in front and rear of the pivot including cylinders mounted on the heel portion of the sole plate, plungers operating in said cylinders and having pivotal connection with the ankle plate, springs in said cylinders and cushioning the downward movement of the pistons in the cylinders, a passageway connecting the lower ends of the cylinders, a valve for controlling the flow of fluid through said passageway from one cylinder to the other, a toe plate pivoted transversely to the sole plate, a frame on the toe plate and extending transversely above the pivotal connection thereof with the sole plate, a spring anchored to the sole plate in rear of the frame, and a ball and

socket connection between the rear of the frame and the upper forward end of the spring.

6. In an artificial limb, the combination with a lower limb portion, an ankle plate secured thereto, a sole plate pivoted at a raised point to the ankle plate, hydraulic cushioning means between the ankle plate and the heel of the sole plate in front and rear of the pivot including cylinders mounted on the heel portion of the sole plate, plungers operating in said cylinders and having pivotal connection with the ankle plate, springs in said cylinders and cushioning the downward movement of the pistons in the cylinders, a passageway connecting the lower ends of the cylinders, a valve for controlling the flow of fluid through said passageway from one cylinder to the other, a toe plate pivoted transversely to the sole plate, a frame on the toe plate and extending transversely above the pivotal connection thereof with the sole plate, a spring anchored to the sole plate in the rear of the frame, a cup mounted in the upper portion of the spring and having a flange engaging around the upper convolution of the spring, a ball seated in said cup for universal movement with the flange extending over the point of largest diameter thereof to retain the ball in the socket, and a rigid connection between the ball and the rear of the toe frame.

7. An artificial foot including an ankle plate adapted for connection with the lower limb portion of an artificial leg, a horizontal pivot positioned centrally beneath the ankle plate, a sole plate, a frame connecting the pivot to the sole plate at a point spaced above the heel of sole plate, cushioning means between the ankle plate and the heel of the sole plate centrally in front and in rear of the pivot connection, a toe plate pivoted at its rear edge transversely to the sole plate, a frame on the toe plate and terminating above the pivotal connection, and a spring connected to the sole plate centrally and extending upwardly to the top of the frame at the rear thereof, and a universal joint connection between the spring and the rear of the toe frame and rigid with the latter.

8. An artificial foot including an ankle plate adapted for connection with the lower limb portion of an artificial leg, a horizontal pivot positioned centrally beneath the sole plate at a point spaced above the heel of sole plate, cushioning means between the ankle plate and the heel of

the sole plate centrally in front and in rear of the pivot connection, a toe plate pivoted at its rear edge transversely to the sole plate, a frame on the toe plate and terminating above the pivotal connection, resilient means connecting the frame of the toe plate to the heel plate at a point spaced rearwardly therefrom, a base plate mounted on the heel portion of the sole plate, cylinders mounted in upright position on the base plate and connected by a passageway in the base plate at the lower ends of the cylinders, pistons movable vertically in said cylinders and having pivotal connection with the ankle plate in front and rear of the pivot thereof, means for controlling the passage of fluid through said passage from one cylinder to the other, and a plurality of cushioning springs in each cylinder between the lower ends thereof and the pistons, and of different tensions, to give varied cushioning action to the pistons in walking.

9. An artificial foot comprising a flat sole plate, an ankle plate transversely pivoted thereto centrally between the front and rear edges of the ankle plate, cushioning means between the ankle plate and the sole plate, a flat toe plate portion pivoted at its rear edge to the front edge of the sole plate, a raised toe frame on the toe plate, and a coil spring connecting the sole plate and the raised toe frame of the toe plate at a point elevated above the pivot of the latter to the sole plate to cause the toe plate to align with the sole plate and clear the ground as the step is completed and the weight of the body is removed from the back foot when walking.
